UNITED STATES PATENT OFFICE

153,889

DESIGN FOR A SHOE OR SIMILAR ARTICLE

Laurel J. Martin, Yucca Valley, Calif.

Application August 3, 1948, Serial No. 147,917

Term of patent 14 years

(Cl. D7—7)

To all whom it may concern:

Be it known that I, Laurel J. Martin, a citizen of the United States, residing at Yucca Valley, in the county of San Bernardino and State of California, have invented a new, original, and ornamental Design for Shoe or Similar Article, of which the following is a specification, reference being had to the accompanying drawing, forming part thereof.

Fig. 1 is a plan view of a shoe or similar article, showing my new design.

Fig. 2 is a side view of the shoe or similar article shown in Fig. 1.

I claim:

The ornamental design for a shoe or similar article, as shown.

LAUREL J. MARTIN.
